Primary Examiner — Melanie H Tung*Assistant Examiner* — Fitzgerald Butac(74) Attorney, Agent, or Firm — Norris McLaughlin & Marcus PA(57) CLAIM

The ornamental design for a refill bottle and wick, as shown and described.

DESCRIPTION

FIG. 1 is a perspective view of front the refill bottle and wick;

FIG. 2 is a plan view of the front of the refill bottle and wick;

FIG. 3 is plan view of the back of the refill bottle and wick;

FIG. 4 is a plan view of a side of the refill bottle and wick;

FIG. 5 is a plan view of a further side of the refill bottle and wick;

FIG. 6 is a plan view of the top of the refill bottle and wick; and,

FIG. 7 is a plan view of the bottom of the refill bottle and wick.

The broken line in FIG. 7 shows a part of the refill bottle that forms no part of the claimed design.

1 Claim, 7 Drawing Sheets(56)
